ABSTRACT

A new *Lantana* plant named 'LANZ0017' having large sized yellow flowers, excellent flower production, compact plant size and uniform dense mounded habit with medium green foliage.

1 Drawing Sheet

1

Latin name of the genus and species of the plant claimed:
Lantana camara L.

Varietal denomination: 'LANZ0017'.

BACKGROUND OF THE NEW PLANT

The present invention comprises a new *Lantana*, botanically known as *Lantana camara L.*, and hereinafter referred to by the variety name 'LANZ0017'.

'LANZ0017' is a product of a planned breeding program. The new cultivar 'LANZ0017' has large sized yellow flowers, excellent flower production, compact plant size and uniform dense mounded habit with medium green foliage.

'LANZ0017' originates from an open hybridization in an outdoor field in August, 2012 in Gilroy, Calif., USA. The female parent was identified as 'LCE0869-2', a unpatented proprietary breeding line, having yellow flower color, and smaller more compact growth habit than 'LANZ0017'. The male parent is unknown.

The seed was sown in December, 2012 in a greenhouse in Gilroy, Calif. and 'LANZ0017' was selected as one flowering plant within the progeny of the stated cross in March 2013.

The first act of asexual reproduction of 'LANZ0017' was accomplished when vegetative cuttings were propagated from the initial selection in June 2013 in a greenhouse in Gilroy, Calif.

BRIEF SUMMARY OF INVENTION

Horticultural examination of plants grown from cuttings of the plant initiated in June, 2013, in Gilroy, Calif., and continuing thereafter, has demonstrated that the combination of characteristics as herein disclosed for 'LANZ0017' are firmly fixed and are retained through successive generations of asexual reproduction.

'LANZ0017' has not been observed under all possible environmental conditions. The phenotype may vary signifi-

2

cantly with variations in environment such as temperature, light intensity, and day length.

A Plant Breeder's Right for this cultivar has not been applied for. 'LANZ0017' has not been made publicly available prior to the effective filing date of this application, notwithstanding any disclosure that may have been made less than one year prior to the effective filing date of this application by the inventor or another who obtained 'LANZ0017' directly from the inventor.

The following traits have been repeatedly observed and are determined to be basic characteristics of the new variety. 15 The combination of these characteristics distinguishes this *Lantana* as a new and distinct variety.

BRIEF DESCRIPTION OF THE PHOTOGRAPHS

20 The accompanying photographic drawings show typical flower and foliage characteristics of 'LANZ0017' with colors being as true as possible with an illustration of this type.

25 The photographic drawings show in FIG. 1 a close view of an inflorescence and in FIG. 2 a whole flowering plant.

DETAILED BOTANICAL DESCRIPTION

30 The plant descriptions and measurements were taken in Gilroy, Calif. in March 2017. The plants were approximately 3 months old and were growing in 4.5" pots in a greenhouse.

35 The aforementioned photographs show those same plants as used for the description were taken in Gilroy, Calif. in April 2017 and show 3 month old plants from an indoor trial.

Color references are made to The Royal Horticultural Society Colour Chart (R.H.S.) 2001.
